UNITED STATES PATENT OFFICE.

HARVEY F. CRAWFORD AND RICHARD C. LAMBERT, OF BROCKTON, MASSACHUSETTS; SAID LAMBERT ASSIGNOR OF ONE-THIRD OF HIS RIGHT TO SAID CRAWFORD.

HYDRAULIC ENGINE.

SPECIFICATION forming part of Letters Patent No. 472,942, dated April 12, 1892.

Application filed February 13, 1891. Serial No. 381,300. (No model.)

To all whom it may concern.

Be it known that we, HARVEY F. CRAWFORD and RICHARD C. LAMBERT, of Brockton, county of Plymouth, State of Massachusetts, have invented an Improvement in Hydraulic Engines, of which the following description, in connection with the accompanying drawings, is a specification, like letters and figures on the drawings representing like parts.

10 This invention has for its object to produce a novel hydraulic engine.

In our invention we employ a pair of hydraulic cylinders, each having its own piston, and connect such pistons with the shaft to be driven. Tubes containing a motor-fluid communicate with these cylinders, and these tubes contain plungers which have a common plunger-rod, and this plunger-rod is reciprocated by a steam-engine, so as to force the 15 motor-fluid first into one cylinder and then into the other, in order to drive the pistons and so rotate the shaft, all as we will proceed now more particularly to set forth and finally 20 claim.

25 Figure 1 represents in side elevation a hydraulic engine embodying this invention; Fig. 2, a top or plan view of the same, partially broken away; Fig. 3, a sectional detail showing the clutch mechanism to be described, 30 and Fig. 4 a modification to be referred to.

Referring to the drawings, the bed A, of suitable shape and construction to sustain the various parts, supports at or near its middle the pillow-blocks A' A² A³, each containing a series of rolls which form bearings for the main crank or driving shaft B, having fast upon its opposite ends the fly-wheel F and driving-pulley D. (See Fig. 2.) Two toothed wheels b b' are loosely mounted upon 35 the shaft B at opposite sides of the middle pillow-block A², they having fast to or formed as a part of them the ratchet-toothed wheels b² b⁵, engaged by spring-controlled pawls a a', pivoted at a² in the heads a³ of the hubs a⁴, fast on the shaft B. The toothed wheels b b' are engaged above and below, respectively, by the rack-teeth upon the inner sides of the piston-rods c c', fast to and moved by the pistons c² c³ in the hydraulic cylinders C C', supported by the bed A. The bed A and pillow-

block A³ are provided, respectively, with guide-rolls 10 12 (shown in dotted lines, Fig. 1) to keep the rack-teeth on the piston-rods c c' in engagement with their toothed wheels. The cylinders C C' are provided with chambers (represented as formed of tubes) C² C³, curved over to face each other, and the said tubes are fitted with plungers C⁴ C⁵, arranged at the opposite ends of the plunger-rod C⁶, which rod at or near its middle is herein shown provided with a laterally-extended stud C⁷, (see Fig. 2,) to which is journaled the outer end of the piston-rod E, connected with and moved by the piston E' in the steam or power cylinder E^X, supported in suitable manner by the bed A. The steam or power cylinder E^X, as usual, is provided with a steam-chest E², in which is placed a suitable valve or valves to control the admission of steam to the steam-cylinder E^X, we having herein represented a main slide-valve V, (shown in dotted lines, Fig. 2,) upon the back of which slides the cut-off valve v, the said valves being actuated by valve-stems V' v', connected by links v² with the actuating-lever b³ at opposite sides of its pivotal center b⁴, the said lever being pivoted or mounted on a boss raised upon the pillow-block A'. The actuating-lever b³ has at its outer free end a slot v³, which receives a stud v⁶ on the plunger-rod C⁶, movement of the plunger-rod communicating the proper movement to the valves V v through the lever b³. Any other desired mechanism may be employed to move the valve or valves, which may be of any desired form or kind other than the particular ones shown. Steam being admitted to the steam-chest E², the piston E' in the steam-cylinder will be reciprocated, transmitting a corresponding reciprocating movement to the plunger-rod C⁶ and plungers C⁴ C⁵, which will force the water or other fluid contained in the chambers or pipes C² C³ alternately into the cylinders C C' behind their pistons c² c³, causing the same to be reciprocated. When the 95 pistons c² c³ are reciprocated by movement of the plungers C⁴ C⁵, the toothed wheels and their ratchet-wheels are given a rotary reciprocating motion by the rack-teeth on the piston-rods, the ratchet-wheels co-operating with 100

the pawls $a a'$ to turn the shaft B in the direction indicated in Fig. 1. As the piston of the steam-cylinder acts on the small plungers $C^4 C^5$, which in turn force the fluid into the 5 hydraulic cylinder behind the pistons therein, great power is obtained, which can be utilized to advantage in a variety of ways.

We do not limit this invention to the particular clutch mechanism shown, as any other 10 suitable clutch mechanism may as well be employed, and even a crank may be substituted for the clutch mechanism, if desired, the pistons being connected to a crank B' on the shaft B by usual connecting-rods $c^x c^x$, as 15 represented in Fig. 4.

If desired, two or more power-cylinders may be employed.

We claim—

1. A bed, the hydraulic cylinders C C', 20 mounted thereon and having pistons, and the

shaft B, rotated thereby, combined with the pipes $C^2 C^3$, plungers $C^4 C^5$, plunger-rod C⁶, the steam-cylinder E^x, and its piston to actuate said plunger-rod, substantially as described.

2. A bed, the hydraulic cylinders C C', 25 mounted thereon and having pistons, and the shaft B, rotated thereby, combined with the pipes $C^2 C^3$, plungers $C^4 C^5$, plunger-rod C⁶, the steam-cylinder E^x, its piston to actuate said plunger-rod, and the valve-actuating lever b³, 30 substantially as described.

In testimony whereof we have signed our names to this specification in the presence of two subscribing witnesses.

HARVEY F. CRAWFORD.
RICHARD C. LAMBERT.
